UNITED STATES PATENT OFFICE

OTTO E. SZEKELY, OF HOLLAND, MICHIGAN

SUPPORT FOR WASHING MACHINES

Original application filed May 2, 1927, Serial No. 188,145. Divided and this application filed November 5, 1927. Serial No. 231,312.

This application is a division of my application filed May 2, 1927, Serial No. 188,145.

This invention relates particularly, though not exclusively, to a support for a washing machine having provision to interlock with or receive certain members of the support.

The object of the invention is to provide a support or frame for washing machines comprising a plurality of separable parts which can be packed separately or with a washing machine in compact form to occupy a minimum of space in shipping, and which can be easily and quickly set up for use.

Another object of the invention is to provide an adjustable support whereby the washing machine may be readily adjusted to different heights by interchanging certain parts of the support.

Another object is to provide a support for washing machines which is simple and durable in construction and which can be readily and economically manufactured.

The accompanying drawing illustrates a selected embodiment of the invention and the views therein are as follows:

Fig. 1 is a perspective view of a washing machine to which the support may be applied.

Fig. 2 is a perspective view of the support.

Fig. 3 is an exploded view of one of the corner members and its cooperating parts.

Referring to the drawings 1 indicates a tub and 2 a motor for driving the mechanism contained in the gear casing 3 to operate the impeller (not shown) arranged in the tub.

A plurality of sockets 4 are connected to the tub and are adapted to receive the support which is designated generally 5.

The support comprises a plurality of four-way T's 6 each having a vertical body member 7 and side branches 8 and 9. The branch 8 of each T 6 is adapted to receive a pipe or other tubular member 10 which is suitably secured thereto, while the branch 9 is split

as at 11 to receive an end of a pipe or other tubular member which is fastened in the branch 8 of an adjacent T. The end of the pipe in each split branch 9 is securely fastened therein by a set screw or bolt 12 passing through aligned holes formed in the lugs

13, 13 which are integrally formed on the branch and on each side of the split 11. A leg 14 fits in the top of each body 7 and it has a tapered upper end 15 to engage a socket 4 on the tub. A caster 16 is mounted in the lower end of each body 7.

A socket member 4' on the gear casing 3 does not have the same relative position as the socket members 4, so a T member 17 is provided of different construction than the fourway T's 6 just described. This T member 17 has a vertical body portion 18 to which a Y 19 is integrally or otherwise connected. This Y has a neck or stem 20 to which side branches 21, 21, are integrally connected at right angles to each other. The neck 20 is of sufficient length to bring the branches 21 thereof in alinement with the branches 8 and 9 of adjacent T's 6. A stub leg 14' having a tapered end 15' is mounted in the top of the body portion 18 of the T member 17 and a caster 16 is mounted in the lower end thereof in the same manner as the legs 14 and the other casters 16 are arranged in the T's 6. By connecting pipes 10 with T's 6 and 17 and attaching the legs and casters, the support may be quickly and completely assembled as shown in Fig. 2. When all of the socket members on the tub are like 4 all the T's will be made like 6 and the legs will be made accordingly.

All of the T's 6 may be made alike so that when the support is assembled the split branch of one T will be opposite a socket or non-split branch of the adjacent T and the pipe 10 will have one end fastened into a socket branch 8 and its other end clamped in a split branch 9.

The legs 14 can be readily inserted in and removed from the members 7 and 18 and sets of legs of different lengths may be provided and interchanged to raise or lower the washing machine. The pipes 10 may be cut to any length desired to provide a support of any size required; or the end pipes may be shorter than the side pipes to provide a long narrow support. I may provide two split branches in each T 6 to receive the pipes, although it has been found preferable to have one end fitted, or otherwise secured, in one branch of the T. A web 22 may integrally connect the side

branches with the body 7 to add strength and rigidity thereto, and the pipes 10 may have tapered ends 23 to facilitate inserting the pipes in the branches.

5 My invention provides a support of novel and simple construction which can be economically produced, which can be easily and quickly assembled without especial skill and which is strong and substantial. It is especially 10 important in reducing the space required for shipping. Only seventy-five to eighty washing machines having the usual supports can be loaded into a freight car of ordinary size, but it is possible to load one hundred to one 15 hundred and ten and even more washing machines provided with a "knock down" support embodying the present invention, in the same car. The cost of handling and transportation is thereby considerably reduced.

20 Changes may be made in the form, construction and arrangement of the parts without departing from the spirit or sacrificing any of the advantages of the invention, and I reserve the right to make all such changes 25 as fairly fall within the scope of the following claim.

I claim:

A rectangular, knockdown, supporting frame for washing machines comprising three 30 tubular corner members, a branch socket integrally connected to each of said members, a split socket branch integrally connected to each of said members and at right angles to said first named branch, a pipe mounted in 35 each of said branches, one end of said pipe being permanently fastened in the first named branch socket in one member and the opposite end removably inserted in the split branch of an adjacent member, a set screw for 40 clamping the pipe in each of said split branches, a fourth tubular corner member having branches disposed at right angles at the corner and connected to the ends of the adjacent pipes, an extension between the 45 branches and said fourth tubular member to offset said member from the corner of the rectangle, legs mounted in the top of said members, and a caster arranged in the lower end of each of said members.

50 OTTO E. SZEKELY.
